CIGAR TIP PERFORATING MACHINE

Martin Caraballo and Joseph G. Zendegui,
Tampa, Fla.

Application June 3, 1935, Serial No. 24,748

7 Claims. (Cl. 131—20)

The present invention relates to improvements in cigar perforating machines, and more particularly has reference to an improved machine for perforating the closed tip ends of cigars to facilitate the draft of the smoke to the smoker's mouth and to dispense with the unpleasant and disagreeable practice of requiring the user to bite off a portion of the tip end of the cigar preparatory to smoking.

10 The invention involves certain improvements over the device shown and described in our prior application filed April 22, 1935 Serial No. 17,703.

An object of the invention is to provide an improved cigar perforating device in which a 15 hollow perforating needle is employed to enter the tip end of the cigar, such needle being tapered to facilitate its entrance with a minimum of disturbance to the structure of the wrapper and filler of the cigar and to insure that the perforation produced by the needle shall be of a substantially conical form with its wider or base end outwardly whereby a better draft will be secured and the likelihood of the perforation becoming clogged is avoided.

20 Another object of the invention is to provide that the cuttings of the tobacco produced by the penetration of the needle are instantly and completely withdrawn by the action of a sufficiently-powerful suction, leaving the perforation clear and clean when the needle is removed and assuring that no particles of tobacco are left behind to be drawn into the smoker's mouth.

25 A further object of the invention resides in the use of a cigar tip receiving head having a truly conical cavity to receive the tip ends of cigars of various sizes, as distinguished from a rounded cavity which will accurately fit only the particular shape of cigar tip conforming to that size.

30 A still further object of the invention is to produce a cigar perforating device adjustable with respect to a gauge table whereby the device may be raised or lowered through the table for accurate alinement with either thick or narrow cigars.

35 A still further object of the invention is to produce a compact organization capable of accurately and quickly perforating large quantities of cigars of various shapes and sizes, wherein the several associated agencies are grouped together in small compass for economical production and operation.

40 With the foregoing and other objects in view, the invention will be more fully described here-

inafter, and will be more particularly pointed out in the claims appended hereto.

In the drawings, wherein like symbols refer to like or corresponding parts throughout the several views:

Figure 1 is a top plan view of a cigar perforating machine constructed in accordance with the present invention.

Figure 2 is a front elevation of the same.

Figure 3 is a vertical section taken on an enlarged scale on the line 3—3 of Figure 1.

Figure 4 is a horizontal section taken on the line 4—4 of Figure 3.

Figure 5 is a similar view showing the needle in the retracted position.

Figure 6 is a side view of the preferred form of needle employed.

Figure 7 is a vertical section taken on the line 7—7 in Figure 3.

Figure 8 is a fragmentary vertical section taken on an enlarged scale on the line 8—8 in Figure 1.

Figure 9 is a fragmentary horizontal section taken on the line 9—9 in Figure 8.

Figure 10 is a fragmentary vertical section through the vacuum receptacle.

Referring more particularly to the drawings, 25 11 represents a table on which the cigars are placed. This table may be constructed in any suitable fashion but it is preferably provided with side flanges 12 and 13 and a back-board 14, 30 the table at the front being left free for the convenience of the manipulations of the operator.

The table may be mounted upon any suitable legs or frame-work 14', which frame-work is also utilized to support a shelf 15.

35 As shown in Figure 2 an electric or other motor 16 is suspended from the shelf 15 so as to be in convenient driving relation to a pump or exhauster 17 carried upon the shelf. The shelf also forms a convenient support for the vacuum receptacle 18 connected by a flexible hose or other conduit 19 with the exhauster 17 and with the cigar cutting implement or device by the flexible tube or other conduit 20.

The receptacle 18 is shown more particularly 40 in Figure 10 and may be conveniently in the form of a glass jar such as a preserving jar, to enable the process to be observed at all times and to note the accumulation of the cigar cuttings, which may be removed from time to time from 45 the receptacle through its screw cover 21. An elbow 22 passes through the cover 21 and terminates in the upper portion of the receptacle 18. The conduit 20 is connected to the external end 50 of this elbow 22.

The other conduit 19 connects with a second elbow 23 passed through the cover 21 and having its inner end disposed within a cylindrical screen 24 carried by a septum or supporting disk 25 held 5 upon the upper part of the jar neck.

Referring more particularly to Figures 3 to 7 inclusive, the flexible vacuum conduit 20 is connected through the intermediary of an elbow 26 with one open end of a hollow plunger 27. The 10 plunger reciprocates in a cylinder 28 which is open at both ends and the plunger 27 is longer than the cylinder, projecting outwardly beyond the same at both ends. At its outer end the cylinder 28 is formed with a shoulder 29 having a 15 perforation 30 therein and an inclined wall 31 leading from the larger internal bore diameter of the plunger 27 to the restricted diameter of the perforation 30. Forwardly beyond the shoulder 29 is a socket 32 also in the plunger for receiving 20 a needle 33 having a rear cylindrical portion to fit snugly within the socket 32 and to abut at its rear end against a shoulder 34 formed by the front wall of the diaphragm 29. The needle is 25 hollow from end to end and has a forward portion 35 of a tapering form for a purpose later to be described. At its free end the needle is cut off diagonally as indicated at 36 to produce an inclined knife edge to facilitate its penetrating the closed tip end of the cigar.

30 Such tip end of the cigar is received within a cavity 37 in a head 38. It is to be noted that the internal wall of the cavity 37 is truly conical. In our prior application, above referred to, the wall of the cavity was rounded or partly spherical for 35 the purpose of accurately fitting the tip or nose of a cigar, but it was found in practice that, while such rounded cavity wall was desirable for the particular size of cigar which fitted the same, it was not so desirable for other types of cigars and 40 would not accurately center thin cigars, such as panatelas, where the head was made for coronas or other larger sizes. It is an important consideration to perforate the tip of the cigar as near centrally as practicable and the truly conical wall 45 37 assists to this end regardless of the size or shape of the cigar tip which is inserted in the head 38. In the head is a lateral opening 39 to admit a set screw 40 threaded in the forward portion of the plunger 27 for engaging and affixing 50 the hollow needle 33 in the socket. The forward tapered portion 35 of the needle slides freely into and out of the cavity 37 of the head 38 through an opening 41 in the head at approximately the apex of the conical wall 37. Back of this conical 55 wall the head 38 is formed with a shoulder 42 against which the forward end of the plunger 27 is adapted to engage.

The head has a cylindrical part of a diameter to fit tightly and slidingly over the plunger 27 but 60 the head 38 does not move back and forth with the plunger 27 but remains stationary with the plunger cylinder 28. For this purpose the rear-most part of the head 38 is cut away internally as indicated at 43 to fit about the rear part of the cylinder 28 to which it may be secured in any 65 appropriate manner as by a clamp collar 44.

The cylinder 28 is carried by a bracket 45 having the perforated arms 46 and 47 to receive therethrough such cylinder 28. The cylinder 28 is 70 moved from the left toward the right into the arms 46 and 47 when assembling the same until the shoulder 48 of the cylinder strikes the arm 46, whereupon the nut 49 is threaded upon the other end of the cylinder and up against the opposite bracket arm 47. It will be understood that 75

where the bracket 45 and the bracket arms 46 and 47 are made of light sheet metal it will be desirable to hold the same in the spaced relation by a spacing sleeve 50 mounted over the cylinder between and abutting against the two bracket 5 arms 46 and 47.

The bracket 45 is secured by rivets or other appropriate fastenings to a vertically adjustable supporting plate 51 mounted to slide in guides 52 of a guide plate 53. This guide plate is riveted 10 or otherwise secured to a portion of the framework as for instance to an angle bar 54 as illustrated in Figure 7.

In this same figure the adjustable supporting plate 51 is shown as having a right-angularly 15 extending foot-piece 54' threadedly engaged by an adjusting screw 55 mounted for rotary movement in the table 11 and having a knurled or other head 56 for facilitating the rotation of the screw. The head 56 lies above the plane of the 20 table top 11, such head resting on a removable plate 57 to take the wear off the table and also to provide a cover for a recess 58 below the plate and made in the table to receive a cotter pin or other key device 59 engaged through the shank 25 of the screw 55 just below the plate for preventing the screw from being lifted and allowing rotation of the screw 55 but preventing its axial movement either up or down. In this way when the screw 56 is rotated it will cause the foot-piece 54' to 30 either climb up upon the same or to descend along its axial length, thereby either raising or lowering the plate 51 and with it the cigar tip perforating device. It will be noted that this device is movable up and down in an opening or slot 60 in the 35 table 11 and that such slot adjoins a groove 61 formed in the table top 11.

The adjustment of the cigar tip perforating device up and down with respect to the slot 60 in the table is made secure by means of a set 40 screw 62 operating through a slot 63 in the guide plate 53 and threaded into the movable supporting plate 51. The set screw 62 is of course loosened before the adjusting screw 56 is manipulated. When the adjustment is completed then the set screw 62 is again set tight to preserve the adjustment.

As shown more particularly in Figures 3, 4 and 7 the plunger 27 and needle are reciprocated back and forth in the cylinder 28 and in the head 38 by link arms 64 and 65 pivoted, as indicated at 66, to the rear projecting portion of the plunger 27 and pivoted, as indicated at 67, at their opposite ends to an arm 68. The two arms 64 and 65 may be secured together as by 55 the rivet 69.

The arm 68 is fixed upon one end portion of a rock shaft 70 mounted in appropriate brackets 71 upon the frame of the machine. This rock shaft is maintained in one position by the action 60 of a coil spring 72 wound about a portion of the shaft 70 with one end affixed to the shaft as indicated at 73 in Figure 7, while the other end 74 is secured to a non-rotative part such as the frame-work of the machine.

At its other end portion, as shown in Figures 8 and 9, the rock shaft 70 carries a bell crank having a horizontal arm 75 and a vertical arm 76. The bell crank is fixed on the shaft 70 and is required to move therewith. The horizontal arm 75 is connected by a pitman 77 with the treadle 78 shown in Figure 2.

The vertical arm 76 of the bell crank as illustrated in Figure 8 carries a block 79 having an opening to slide on a rod 80 supported in a 75

bracket 81 and being threaded to receive the adjusting nuts 82 and 83 for the purpose of adjusting and moving the rubber or other resilient or soft stops 84 and 85 toward and from the block 79. By adjusting the stops the limit of traverse of the needle may be restricted in either direction and its degree of penetration is thus regulated.

The tip perforating device is preferably enclosed, to exclude dirt, dust and foreign matter, by a casing 86 having a front opening 87 through which the head protrudes, and a side opening 88 to admit the hand to the adjusting screw 62.

15 In operation, an operator sits at the table 11 with the cigars to be treated preferably placed at the left side of the perforating device while those cigars having been treated are placed to the right of the device upon the table, from 20 which they may be removed from time to time for packaging and shipment. The cigars are taken singly, placed in the elongated groove 61 of the table, which is of such size and shape as to form a gauge or centering device for the cigars 25 with reference to the perforating device.

The tip end of the cigar is placed rearward and it is moved by the operator into the cavity 37 of the head 38 while the needle is in a retracted position. The treadle 78 is then stepped 30 upon by the operator causing the rock shaft to be moved as indicated in Figure 8. This movement is accompanied by the forward thrust of the tapered part 35 of the needle out through the cavity 37 of the head 38 and into the closed 35 tip end of the cigar. Promptly after this movement the treadle is released and the coil spring 72, which has been wound so that it possesses potential energy because of the state of tension by the forward rocking movement of the shaft 40 76, now unwinds, causing the restoration of the parts to the rearward position and causing the needle, or rather the tapered portion 35 thereof, to retire from the cavity 37 and from the cigar tip it has but lately entered.

45 During all of this time the electric motor 16 has been driving the exhauster 17 which has placed the receptacle 18 under a condition of partial vacuum. This condition is transmitted by the conduit 20 to the interior of the hollow plunger 27 and the hollow needle 33; whereby 50 as the needle is moved forwardly, penetrating the cigar tip and cutting its way into the tobacco leaf and filler, the cuttings and the particles of the tobacco removed by this action of the needle are withdrawn rapidly and effectively by the vacuum through the hollow needle and the hollow plunger 27 and into the receptacle 18.

The screen 24 in the receptacle 18 will prevent these cuttings from being drawn out through 60 the conduit 19 and into the exhauster and will require that the cuttings fall to the bottom of the receptacle 18. The accumulation of these cuttings may be observed and removed from time to time.

65 By virtue of the tapered portion 35 of the needle the entrance of the needle into the cigar tip will be facilitated. Not only its entrance but also the withdrawal of the needle will be accomplished without disrupting the structure of the 70 cigar tip. Moreover this tapered form in entering will tend to back the loose parts of the filler against the side walls of the perforation made, as the tapered form will have a wedging action. The inclined end 36 will create a shearing effect 75 as this inclined end is driven into the cigar and

it will also offer a wider port area for the action of the suction than would be had if the port were at right angles to the axis. The larger bore of the plunger 27 behind the more restricted diameter of the hollow needle places the full force 5 of the suction immediately behind the needle and also prevents clogging, as might occur with smaller passages.

For thin cigars, such as panatelas, it will be desirable to lower the perforating device through 10 the slot 60 in the table to enable the needle to become centered with respect to the cigar.

At other times with cigars of great diameter it will be desirable to elevate the perforating device so that in these cases also the needle will 15 perforate centrally the tip. The adjusting device 56 provides for these changes in elevation of the perforating device. The adjustment may be made quickly and easily. Also the degree of penetration of the needle may be adjusted easily 20 and quickly by the device shown in Figures 8 and 9 and thus a perforation in the cigar tip at the proper position and of the proper depth may be had. A single operator may perforate large quantities of the cigars with this device for the 25 reason that once the adjustments have been made, it only becomes necessary to place the cigars one after another in the groove 61, push the same into the cavity 37 of the head and then depress the treadle 78 and subsequently remove 30 the foot from the same. The vacuum arrangement will automatically take care of removing the cigar cuttings, leaving a clean and clear perforation; while the coil spring 72 will automatically take care of restoring the parts to the initial 35 position in readiness for subsequent actuation upon a following cigar.

After perforation the cigars are then wrapped or packaged, and by reason of the perforations they are more desirable articles of commerce in 40 that the user is not required to use a cigar cutting implement or to indulge in the objectionable practice of biting off the closed tip end of the cigar before he is able to indulge himself in the use of the same.

45 It will be obvious that various changes may be made in the construction, combination and arrangement of parts which could be used without departing from the spirit of our invention and we do not mean to limit the invention to such details 50 except as particularly pointed out in the claims.

Having thus described our invention, what we claim and desire to secure by Letters Patent of the United States is:

1. A cigar perforating machine comprising a 55 table having a slot, cigar perforating means, and an adjustable support for elevating and lowering the perforating means through said slot.

2. A cigar perforating machine comprising a 60 table having a cigar receiving groove and a slot adjoining the groove, cigar perforating means, and an adjustable support for elevating and lowering the perforating means through said slot.

3. A cigar perforating machine comprising a 65 table having a cigar receiving groove and a slot adjoining the groove, guides in the slot, a support movable in the guides, adjusting means to raise and lower the support in the guides, and cigar perforating means carried by said support.

4. A cigar perforating machine comprising a 70 slotted table, guides in the slot of the table, a plate movable in the guides, an adjusting screw rotatable in the table and having connection to said plate to raise and lower the same, a bracket 75

on the plate, and a cigar perforating device carried in the bracket.

5. A cigar perforating machine comprising a cigar tip receiving head, a perforating device movable in and out of said head, an operating means for said device, and adjustable stops for limiting the throw of said device in either direction.

10. A cigar perforating machine comprising a cigar tip receiving head, a perforating device movable in and out of said head, a rock shaft, a connection between said rock shaft and device, a treadle for operating said rock shaft, an arm mov-

able with said rock shaft, and adjustable resilient stops for engaging the arm.

7. A cigar perforating machine comprising a table for supporting the cigars, hollow cigar tip perforating means vertically adjustable through 5 said table, suction means connected to said perforating means to withdraw the cigar cuttings a rock shaft connected to reciprocate said perforating means, and a treadle for operating said rock shaft.
